UNITED STATES PATENT OFFICE.

CHARLES HOWELL, OF CLEVELAND, OHIO, ASSIGNOR TO PETER HANNAY

IMPROVEMENT IN MACHINES FOR PULVERIZING QUARTZ, &c.

Specification forming part of Letters Patent No. 37,322, dated January 6, 1863.

To all whom it may concern:

Be it known that I, CHARLES HOWELL, of Cleveland, in the county of Cuyahoga and State of Ohio, have invented a certain new and Improved Method of Crushing and Pulverizing Quartz and Similar Substances, of which the following is a full, clear, and exact description, reference being had to the accompanying drawings of the same, making part of this specification, of which—

Figures 1 and 2 represent side elevations of my improved machine; Fig. 3, a plan of the same. Fig. 4 represents a side elevation of the machine with one end of the crushing-cylinder removed to show the construction of its parts; Fig. 5, a plan of the interior surface of the cylinder, and Fig. 6 a modification of the same.

The principle of my invention consists in reducing the quartz or similar material to powder by percussion—that is to say, by the sudden check of the momentum of the quartz, &c., moving with immense velocity. This principle I carry into effect by means of a series of beaters mounted on a shaft or disk rotating with great rapidity within a closed cylinder, either smooth or provided on its interior surface with teeth, against which the quartz or similar material is driven with great speed and force by the beaters, and thereby reduced to dust or powder.

To enable others skilled in the art to make, construct, and use my improvement, I will now proceed to describe its construction and operation in detail.

The crushing or pulverizing apparatus may be mounted on any suitable frame. In this instance it is represented as consisting of two supporting-beams, A, on which are erected four upright standards, B—two on either side—connected together at top by beams c, and these, in turn, connected and braced together by cross-rails D, on which are secured bearings E, in which rests and revolves a shaft, F, on one end of which is mounted an armed disk, G, and on the other a driving-pulley, H. The disk G is inclosed by a casing, I, consisting of a cylinder, J, in this instance represented in the drawings as being armed on its interior, with teeth, either of triangular form, as shown in Figs. 4 and 5, or pyramidal teeth, as shown in Fig. 6, (but they may be made in any other suitable form, or, instead of teeth, the inner

surface of the cylinder may be left smooth, but I deem the teeth better,) and two end caps or covers, K and K', the case being firmly and permanently secured to the frame of the machine by means of screw-bolts a and nuts b. On the end K, next the frame of the machine and through its center, is cut a circular opening, through which the shaft F passes, while in the outer end, K', of the cylinder, and at its center, is cut another circular opening, but of larger size, for the purpose of feeding the quartz or other material to the machine, to be pulverized, for which purpose a hopper of suitable shape and dimensions may be attached to the machine, although not represented in the drawings. At or near the inner periphery of the cylinder is cut through either end, but in this case the inner end or disk, K, of the casing I, another opening, to which is secured a carrying-tube, L, through which is forced the pulverized quartz or other substance as fast as ground, and by it conducted wherever desired. In this instance the arms or beaters, for the purpose of strength and to lighten as much as possible their weight, are represented as being cast on a disk, G, which tapers from the shaft F outward; but, if desired, they may be cast on a hub, or in any other suitable manner, consistent with strength; or they may either be made flat or curved, but smooth on their face. The shape of the disk on which they are cast (when a disk is used) may be made in such form as soonest to bring the rebounding pieces of quartz back to the action of the arms or beaters again, and by them forced with great velocity on the teeth. The beaters or arms may be made in such form, whether straight or curved, as may be most conducive to strength and ability to withstand the force of the blow and to act on the pieces of rock, &c. Where teeth d are formed on the inner periphery of the cylinder, I prefer to make them inclined—that is to say, at an angle other than a radial line drawn with the shaft of the disk as a center—while the cylinder itself is concentric with the disk, and so with the arms of the disk, neither being radial, but so that the blow of the beaters or arms e of the disk will force or throw the rocks or stones with immense force and velocity outward toward the toothed cylinder, this being preferable to radial arms or beaters, although the latter may be used with great success. In other words, the face of the teeth

ought to be at right angles to the direction of the quartz or other substance as it is forced from the beaters or arms, under which circumstances they may either be made to run straight across the cylinder, as in Fig. 5, or be cut up somewhat of pyramidal form, like Fig. 6, so that the whole momentum of the quartz or similar material may be checked at once.

In order to make the casing of the beaters perfectly tight and strong, the ends or caps K and K' are made to fit tightly over its ends, and the whole, bolted firmly to the frame. Such a machine is capable of reducing gold-bearing quartz, sand, and similar materials, for various purposes, to a fine powder.

Other formal variations in the construction of the various parts of the machine and of operating them could be described, but I do not deem it necessary to do so, nor do I deem them unprotected by this patent.

The operation of the machine is as follows: The quartz or similar material, broken to a suitable size, is fed in by hand or by means of a hopper through the opening in the outer cap, K, whence it is driven with immense force and velocity by the arms or beaters c on the disk G against the cylinder I, toothed or otherwise, and there reduced to powder, such parts as may not have been completely pulverized rebounding back and again forced by the beat-

ers against the cylinder until it has been perfectly reduced, whence it is carried and discharged by centrifugal force, and the blast generated by the beaters or by other means suitably arranged for that purpose, through the tube L, and by it conducted wherever desired.

If desired, the cylinder may be made to rotate to increase the speed in the opposite direction to the beaters, in which event the machine would require to be suitably constructed for that purpose.

I claim—

Reducing minerals, bones, and similar substances to powder by percussion, substantially as described—that is to say, by means of a rotating projector and an impinging surface, both inclosed in a case, the relations of the rotating projector and the impinging surface being such that the materials will not be pulverized by being crushed between them, but only by the percussion resulting from the sudden checking of the motion given to the materials by the one against the surface of the other, substantially as described.

In testimony whereof I hereunto set my hand this 7th day of June, A. D. 1860.

CHAS. HOWELL.
